(57) **CLAIM**

I claim the ornamental design for the “quencher friendly”
waistpack holder with adjustable web belt, as shown and
described.

DESCRIPTION

FIG. 1 is a front elevation view of the quencher friendly
waistpack holder with adjustable web belt showing my new
design.

FIG. 2 is a rear elevation view thereof;

FIG. 3 is a top plan view thereof;

FIG. 4 is a bottom plan view thereof; and,

FIG. 5 is a side elevation view, with the opposite side being
a mirror image.
